UNITED STATES PATENT OFFICE.

HANLEY HENOCHE, OF NEW YORK, N. Y., ASSIGNOR TO ONONDAGA POTTERY COMPANY, OF SYRACUSE, NEW YORK, A CORPORATION OF NEW YORK.

DESIGN FOR A PLATE OR SIMILAR ARTICLE OF MANUFACTURE.

Application filed March 17, 1925. Serial No. 12,749. Term of patent 14 years.

To all whom it may concern:

Be it known that I, HANLEY HENOCHE, a citizen of the United States, residing at New York, borough of Manhattan, county of New York, and State of New York, have invented a new, original, and ornamental Design for Plate or Similar Article of Manufacture, of which the following is a specification, reference being had to the accompanying drawing, forming a part thereof.

The figure is a plan view of the plate or

similar article of manufacture showing my new design.

I claim:—

The ornamental design for a plate or similar article of manufacture substantially as shown.

In testimony whereof, I have hereunto signed my name, at New York, borough of Manhattan, county of New York, and State of New York, this 9th day of March, 1925.

HANLEY HENOCHE.
